UNITED STATES PATENT OFFICE.

WILLIAM E. GREATHOUSE, OF MASON, OHIO.

FEED-BOX.

SPECIFICATION forming part of Letters Patent No. 546,010, dated September 10, 1895.

Application filed February 2, 1895. Serial No. 537,134. (No model.)

To all whom it may concern:

Be it known that I, WILLIAM E. GREATHOUSE, a citizen of the United States, residing at Mason, in the county of Warren and State of Ohio, have invented a new and useful Knockdown Feed-Box, of which the following is a specification.

My invention relates to improvements in feed-boxes for horses and other animals which can be easily and quickly knocked down—that is, taken apart and packed in a small space for carrying or shipping from place to place—and can easily and quickly be put together again for use. I attain these objects by devices illustrated in the accompanying drawings, in which—

Figure 1 is an isometric view of one style of box set up ready for use. Fig. 2 is an enlarged elevation of seam which joins the sides to the bottom. Other shapes and dimensions may be made in the same manner as that shown, using same seams and catches.

These feed-boxes are preferably made of heavy sheet metal bent into the shape shown and others that may be desired.

In Fig. 1, A, B, C, and D are the sides and E the bottom of box. The bottom is joined and held to the sides by a loose seam *a*. (Shown enlarged in Fig. 2.) These seams or joints are made so that the parts can be moved longitudinally on each other. Each end of the sides B and D is made a little longer than the box. This portion is turned inward at right angles and laps over the sides A and C, as shown at *b* and *c*. In the top of the sides C and A are

mounted the stiff wire rods F and G. These rods are hinged at point of attachment, and their ends can be moved up or down. They are provided, one with hooks in each end and one with eyes in each end, and are shown in the drawings as hooked together outside the upper edge of the sides B and D, thus holding the tops of the four sides securely together.

The method of knocking down or taking apart is as follows: The hooks on wire F are disengaged from the eyes on the wire G and the ends of wires are raised up to a perpendicular position or may be turned a little outward from the box. This allows the sides B and D to drop outward somewhat. The sides B and D are then easily drawn out by pulling them endwise, the loose seams allowing the sides to slip on the bottom. Sides A and C are then drawn out likewise. To set up the feed-box again the operations mentioned above are reversed and the box is again ready for use.

I claim—

In knock down feed-boxes the two opposite sides A. C. having hinged stiff wires F G in their upper edges and being joined to the bottom E with loose seams *a* in combination with two opposite sides B and D having their sides extended a little above the stiff wires F and G and all being joined to the bottom E with loose seams, substantially as and for the purpose set forth.

WM. E. GREATHOUSE.
